UNITED STATES PATENT OFFICE.

CLARA H. HAVEMEYER, OF SPRINGFIELD, MASSACHUSETTS, ASSIGNOR TO PACKAGE PAPER AND SUPPLY CORPORATION, A CORPORATION OF MASSACHUSETTS.

DESIGN FOR PAPER.

• 60,535.

Specification for Design.

Patented Mar. 7, 1922.

Application filed October 19, 1921. Serial No. 508,875. Term of patent 3½ years.

To all whom it may concern:

Be it known that I, CLARA H. HAVEMEYER, a citizen of the United States, residing at Springfield, in the county of Hampden and State of Massachusetts, have invented a new, original, and ornamental Design for Paper, of which the following is a specification, reference being had to the accompanying drawing, forming a part thereof.

The figure is a view of a piece of paper, embodying my new design.

I claim:

The ornamental design for paper, as shown.

CLARA H. HAVEMEYER.
